UNITED STATES PATENT OFFICE

HARRY HARRIS, OF MIAMI, FLORIDA, ASSIGNOR OF THREE-FIFTHS TO TREMAYNE FORBES, OF MIAMI, FLORIDA

MULTIGRAPH MACHINE

Application filed December 6, 1929. Serial No. 412,122.

This invention relates broadly to printing machines, and has more particular reference to certain new and novel and useful improvements in multigraphing machines.

5 A primary object of this invention is therefore to provide a machine of the character above referred to and improved type or embossed printing plate capable of use either on the conventional drum of a multigraph machine, or which may be used on a particular drum designed especially for use with said plates, whereby the plates may be used in the same manner as used when affixed to the conventional drum of a multigraph machine.

10 A still further object of the invention is to provide a machine of the character above mentioned, which will eliminate in multigraph machines the use of numerous individual type as has heretofore been used with such machines, and whereby the disadvantages of other types of machines, such as and principally the D-4 dupligraph machine due to the fact that the maximum size of 15 the paper which could be used in printing with such types of machines was ordinary letter size, these types of machines, and especially the D-4 dupligraphing machine being unable to accommodate foolscap.

20 As is well known in the art, the dupligraph-printing machine uses a block printing plate which is embossed on a graphotype, and it is a primary object of this invention to circumvent the disadvantage of 25 printing with plates on a dupligraph.

30 Other objects and advantages of the invention will become apparent during a study of the following description taken in connection with the accompanying drawings, 35 wherein:

Figure 1 is an elevational view of the invention, the same being shown applied to the conventional segmental multigraphing drum now in use.

40 Figure 2 is a transverse sectional view taken therethrough.

45 Figure 3 is a perspective view of a printing plate as comprehended by the present invention.

Figure 4 is a transverse sectional view through the plate.

Figure 5 is a top plan view of a bracket member to be hereinafter referred to more in detail.

55 With reference more in detail to the drawings, it will be seen that for the purpose of exemplification, I have shown my invention used with a conventional segmental type of multigraph drum now in use, and designated 60 in the drawings generally by the reference character 5.

While I have shown the invention, and will hereinafter describe the same in conjunction with a drum of this character, it 65 is to be understood that I do not limit myself to this precise type of drum, but on the other hand, intend that the invention is capable of use with a drum especially constructed and adapted therefor.

70 The present invention comprehends the provision of what may be termed generally as blankets as herein designated generally by the reference character 6. This blanket 75 6 is formed of a suitable metal plate curved longitudinally as to be somewhat semi-cylindrical in cross section, and is adapted to be disposed over the drum resting on the T-headed ribs or rails 7 of the drum as shown to advantage in Figure 2.

80 At its opposite transverse end the metal blanket 6 is bent inwardly, then upwardly to provide internal channels 8 for reception of the heads of one of the T-shaped ribs or rails 7 at diametrically opposite sides of the 85 drum, as also shown to advantage in Figure 2. Thus, as is apparent, the blanket 6 will be retained on the drum.

From a study of Figure 1, it will be seen 90 that the blanket 6 is of a width less than the width of the drum 5 and the purpose of this will be hereinafter more fully set forth.

95 The invention further comprehends the provision of what may be termed printing plates, which printing plates are designated generally by the reference character 9. These printing plates 9 are preferably formed of zinc and are of elongated rectangular configuration, said plates 9 being of a length greater than the width of the 100

blanket 6 and of suitable width as to enable a plurality of such plates to be arranged over the blanket and secured to the drum in edge to edge relation in a manner to be hereininafter more fully set forth.

At their opposite ends, and as shown to advantage in Fig. 3, these plates 9, adjacent to their opposite ends, are offset laterally to provide shoulders 10—10 and offset ends 11—11.

Each of the plates 9 are suitably embossed to form the raised letters 12 thereon, and of course, these raised letters 12, when the plate is so embossed, make up or constitute a suitable legend, the legend on each of the plates embodying certain sentences or paragraphs of which the finished letter or printed matter will consist.

It is to be further noted that in their finished form, these plates 9 are curved transversely as shown to advantage in Fig. 4 so as to conform with the periphery of the blanket 6.

In actual practice, the blankets having been placed on the drum 5 as hereinbefore mentioned and set forth in detail, the plates are placed on the blanket in edge to edge relation, with their lateral ends 11—11 resting on the ribs or rails 7 of the drum at opposite sides of the blanket and marginal retaining bands 13 are then disposed over the drum and over the lateral end 11 of the plate 9 as shown to advantage in Figure 1 for retaining the plate in position upon the blanket and drum.

These marginal bands 13 are of the same type of band as is used with multigraph machines, as is well known. Of course, the blanket 6 is disposed between the shoulders 10 of the plates 9 and form a raised surface for the plate with respect to the surface of the drum, so that the lateral ends 11 of the plates 9 will rest on the ribs or rails of the drum and the main body portion of the plates 9 will rest on the blanket 6. In this connection, it will be then noted that the body or intermediate portion of the plates 9 will be disposed on a plane above the plane of the lateral end 11 of the plate so that the marginal bands 13 will be lower than the main or intermediate portion of the plate and consequently an outline of these marginal bands will not show up in printing, and the shoulders 10 of the plates, not only permit of the plates having their ends 11 resting flat on the drum, but also so that when the marginal bands are placed thereon, the said bands will be low enough that as before intimated, they will not show up in printing.

Of course, it is understood that the plates 9 must be made of comparatively thin material, and therefore the plates with the embossing on them will not of themselves be of sufficient height as to become type-high so

that they will present a printing surface. To this end the blankets upon which the type rest support or raise the plates substantially type-high thus affording a sufficient printing surface.

From the foregoing then it will be seen that by the use of this blanket 6 and the embossed plate 9, with a multigraph machine, in a manner herein pointed out, the need of individual types for the multigraph machine is eliminated, thus greatly reducing the amount of work as would be involved in setting the type when the multigraph machine is to be used, consequently resulting in a saving of great time and in an increased output.

Another very important advantage of this invention as will be appreciated, is the fact that an invention of this character will eliminate the expense of keeping a great quantity of type on hand as is necessary for operating such types of printing machines as multigraph machines.

It will be also appreciated, that my invention is capable of use with a multigraph machine without necessitating any material change in the basic structure of the machine nor in the operation of the machine, other than the elimination of the need of setting type for the machine.

The plates 9 when shaped and formed as shown and described, and after being embossed through the medium of a conventional embossing machine or graphotype may be readily and easily assembled on the drum of the multigraph machine.

It is believed that from the foregoing, a clear understanding of the operation, construction, utility and advantages of an invention of this character will be had without a more detailed description thereof.

Even though I have herein shown and described the preferred embodiment of my invention, it is to be understood that the same is susceptible to certain changes fully comprehended by the spirit of the invention as herein described, and the scope of the appended claims.

Having thus described my invention, what I claim as new is:

1. In a printing machine of the class described and in combination, a drum having raised ribs or rails integral therewith, a blanket member comprising a metallic plate adapted for disposition on said drum and provided with means cooperable with said ribs for detachably securing said blanket member to said drum, a plurality of embossed plates adapted to be arranged in edge to edge relation on said blanket member and extending transversely thereof, the ends of said plates being offset and adapted for rest on the ribs of said drum, and retaining means engageable with the drum

and the offset ends of said plates for retaining the latter in position.

2. In a printing machine of the class described, and in combination, a drum having a plurality of spaced transverse ribs or rails integral therewith, a blanket member comprising a plate adapted for disposition on said drum, said plate provided with internal channels for receiving certain of said ribs or rails, a plurality of embossed plates adapted to be arranged on said drums transversely of the latter, said plates having intermediate portions for accommodating said blanket member, and the ends of said plates being offset relative to said intermediate portions for rest on the ribs or rails of said drum, retaining means engageable with said drum and offset ends of said plates for retaining the latter in position, said blanket forming member being of a width less than the length of said plates, and the offset ends of said plates extending beyond the adjacent edges of said blanket forming member.

3. In a printing machine of the class described, and in combination, a drum, a blanket forming member to provide a smooth periphery for said drum, said blanket forming member and said drum provided with cooperating means to provide a detachable connection between said blanket forming member and said drum, a plate having printed characters thereon adapted for rest on said blanket forming member transversely of the latter, the ends of said plate being offset and adapted to rest on said drum, retaining means engageable with said drum and offset ends of said plate for retaining the latter in position, said plate being of a length greater than the width of said blanket forming member, and said plate being curved transversely for rest on said blanket forming member conformably with said blanket forming member.

In testimony whereof I affix my signature.

HARRY HARRIS.
